UNITED STATES PATENT OFFICE.

WILLIAM EDWARD CLEMENTS, OF OROVILLE, CALIFORNIA, ASSIGNOR OF ONE-HALF
TO ABRAM C. PENNER, OF OROVILLE, CALIFORNIA.

ELECTRODE-HOLDER.

1,353,028.

Specification of Letters Patent. Patented Sept. 14, 1920.

Application filed March 9, 1920. Serial No. 364,560.

To all whom it may concern:

Be it known that I, WILLIAM E. CLEMENTS, a citizen of the United States, and a resident of Oroville, in the county of Butte 5 and State of California, have invented a new and Improved Electrode-Holder, of which the following is a full, clear, and exact description.

This invention relates to improvements in 10 electrode holders, and more particularly to electrode holders designed for electric welding, an object of the invention being to provide an improved construction of fork consisting of two spring members adapted to 15 grip an electrode between them, said members so shaped transversely as to give a three-point contact engagement with the electrode, thereby securely holding the electrode, but permitting the latter to be positioned at any desired angle in accordance 20 with the operation to be performed.

A further object is to provide a device of the character stated which is of simple construction and which is most efficient in 25 performing the functions for which it is intended.

With these and other objects in view the invention consists in certain novel features of construction, and combinations and arrangements of parts as will be more fully 30 hereinafter described and pointed out in the claims.

In the accompanying drawings—

Figure 1 is a view in elevation illustrating my improved device;

Fig. 2 is a view in longitudinal section on the line 2—2 of Fig. 1; and

Fig. 3 is a view in transverse section on the line 3—3 of Fig. 1.

1 represents a head or coupling member which is provided in its inner end with a recess 2 in which wires 3 of a flexible cable 4 are secured by solder or other approved means. The recessed inner end of the head 45 or coupling member 1 is reduced in diameter externally forming an annular recess 5 receiving the end of a tubular handle 6. This handle 6 is preferably of fiber or other suitable non-conducting material and is rigidly secured to the head or coupling member 1 by means of a countersunk screw 7 projected through the handle 6 and screwed into a threaded socket 8 in the head 1.

The head 1 is preferably of copper or

other similar conducting material and is 55 provided in its outer end with a screw threaded recess 9 receiving the threaded end 10 of my improved fork 11. The fork 11 is split longitudinally forming a pair of gripping jaws 12 and 13, these jaws being normally together, and the fork composed of 60 spring metal so as to exert a gripping action on an electrode 14 when the latter is forced between the jaws 12 and 13.

The jaws 12 and 13 are curved transversely and the curvatures of the jaws are concentric with each other so that when the electrode 14 is positioned between the jaws, the edges of one jaw will engage the electrode and clamp the latter against the intermediate portion of the other jaw. This construction provides a three-point contact between the fork and the electrode and such a contact not only insures a firm gripping action, but also permits the electrode to be 75 positioned at any desired angle relative to the fork as indicated in Fig. 1, and be securely clamped in any position.

In operation, the electrode 14 is forced between the jaws 12 and 13 and moved inwardly until the desired gripping action is had, the elasticity of the jaws serving to securely clamp the electrode as above explained.

Various slight changes may be made in 85 the general form and arrangement of parts described without departing from the invention, and hence I do not limit myself to the precise details set forth, but consider myself at liberty to make such changes and 90 alterations as fairly fall within the spirit and scope of the appended claims.

I claim:

1. An electrode holder, comprising a fork having a pair of jaws projecting longitudinally of the fork, one of said jaws curved transversely and adapted to clamp an electrode against the other jaw, thereby providing a three-point contact between the fork and the electrode.

2. A device of the character described, comprising a fork split longitudinally and forming a pair of spring jaws, said spring jaws curved transversely and concentrically.

3. An electrode holder, comprising a fork having a pair of jaws projecting longitudinally of the fork, one of said jaws having a longitudinally extended single electrode con-

tacting portion, and the other jaw having a plurality of longitudinally projecting electrode contacting portions.

4. A device of the character stated, comprising a head or coupling member having recesses in its respective ends, an electric conductor secured in one of the recesses, a tubular handle of non-conducting material located around the conductor and secured 10 to the head or coupling member, and a fork

removably secured in the other of said recesses in the head or coupling member, said fork split longitudinally and forming a pair of jaws adapted to receive an electrode between them, said jaws curved transversely and concentrically, whereby said jaws have a three-point contact with an electrode when the latter is positioned between them. 15

WILLIAM EDWARD CLEMENTS.
